Primary Examiner—Raphael Barkai(74) *Attorney, Agent, or Firm*—Edward W. Callan**(57) CLAIM**

The ornamental design for a toy building element, as shown and described.

DESCRIPTION

FIG. 1 is a top perspective view of the toy building element. FIG. 2 is a front view of the toy building element shown in FIG. 1, the rear view being identical.

FIG. 3 is a top view of the toy building element shown in FIG. 1.

FIG. 4 is a left side view of the toy building element shown in FIG. 1, the right side view being identical.

FIG. 5 is a bottom perspective view of the toy building element shown in FIG. 1.

The bottom view does not form part of the claimed design.

UNITED STATES PATENT AND TRADEMARK OFFICE
CERTIFICATE OF CORRECTION

PATENT NO. : Des. 470,196 S
DATED : February 11, 2003
INVENTOR(S) : Soren Christian Sorensen

Page 1 of 1

It is certified that error appears in the above-identified patent and that said Letters Patent is hereby corrected as shown below:

Title page.

Before "DESCRIPTION", the following should be inserted:

-- BRIEF DESCRIPTION OF THE INTENDED USE OF THE ARTICLE IN WHICH THE DESIGN IS EMBODIED:

It is intended that the toy building element of the present invention be used in a set of toy building elements that are capable of being interconnected in a releasable engagement. --

Signed and Sealed this

Fifth Day of August, 2003

JAMES E. ROGAN
Director of the United States Patent and Trademark Office
